UNITED STATES PATENT OFFICE.

SYDNEY L. BROWN, OF BROOKLYN, NEW YORK.

EMBOSSING MACHINE.

Application filed October 24, 1925. Serial No. 64,597.

This invention relates to a machine or apparatus for embossing strips of soft metal or other suitable material. The invention has been made especially with the idea of 5 providing a machine for ornamenting the outer or side surfaces of window bars, or cames, used for mounting the panes of leaded glass windows, and which are usually made of lead or other soft plastic metal. Lead 10 cames are usually made by extruding metal through dies to form long rods H shaped in cross-section, the rods being cut into suitable lengths for handling. Such cames as extruded from the dies are not suitable for use 15 where artistic effects are desired. An object of the present invention is to provide a machine whereby an ornamental surface formation may be given to the sides of the came, and especially to produce cames having the 20 form and appearance of hand wrought cames. An important feature of the invention is that the machine does not form the cames with a fixed repeated pattern.

In accordance with the invention, the sides 25 of the came are shaped or embossed by means of pattern units each comprising a plurality of, usually two, pattern wheels mounted side by side so as to provide a peripheral embossing surface which presses 30 against the side of the came as the wheels roll against the came.

A full understanding of the invention can best be given by a detailed description of an 35 approved embodiment of the features of the invention, and such a description will now be given in connection with the accompanying drawings illustrating such an embodiment, in which:—

Fig. 1 is a view of a machine for embossing cames of lead or the like showing the 40 machine in elevation and showing in section a came in position in the machine;

Fig. 2 is a plan view of the machine;

Fig. 3 is a detail view on a larger scale 45 showing in section one of the pattern units and part of the other pattern unit and parts of the feeding wheels;

Fig. 4 is a still further enlarged sectional 50 detail view showing cooperating portions of the pattern units and feed wheels;

Fig. 5 is a similar view but sectioned with the pattern units turned to a different position to illustrate the difference in formation 55 of different portions of the peripheral embossing faces of the pattern wheels;

Fig. 6 is a view of a short length of came as it comes from the extruding die; and

Fig. 7 is a view of one side of the completed product of the machine.

Referring to the drawings, the operative 60 parts of the machine as shown are carried by two standards 10 and 11. Two feeding disks or wheels 12 and 13 are secured on horizontal driven shafts 14 and 15 respectively which are mounted in bearings on the 65 standards 10 and 11. These shafts may be driven in any suitable manner. The feeding wheels in the machine shown are set one above the other in the same vertical plane. Their peripheries are spaced just sufficiently 70 to receive between them, and to have a feeding grip on, the web of the came so as to feed the came horizontally between the wheels, and the wheels are of a thickness at 75 and near their peripheries to fill the channels in the came and to serve as supports for the side walls of the came.

On each side of the path of the came as it is fed along by the wheels 12 and 13 there is mounted a pattern unit consisting of two 80 independently rotatable pattern wheels 20 and 21 mounted side by side to roll against the side of the came as it is moved by the feeding wheels, each pattern wheel bearing on a portion of the came side. When 85 the feeding wheels are mounted as shown with their axes horizontal and in the same vertical plane, the pattern wheels of both units will be mounted with their axes extending vertically and in the same vertical 90 plane and with the pattern wheels of each unit mounted one above the other. The two pattern wheels of each unit are desirably of the same diameter and mounted on a common shaft 22 carried by upper and lower 95 boxes 23 and 24 which are mounted to slide horizontally in inwardly extending upper and lower extensions 25 and 26 of the standards 10 and 11. The boxes 23 and 24 are pressed inward by springs 27 to force the 100 pattern wheels inward toward the feeding wheels to bear with suitable pressure against the sides of the came.

One of the pattern wheels, 20, is formed with an inwardly tapered lateral extension 105 30 of its peripheral surface, and the other wheel, 21, has a lateral flange 31 which extends over the lateral extension 30 and has an undulating edge, the inner face of the flange 31 being outwardly tapered and the 110

parts being formed and proportioned so that the flange 31 will lie over and close to but out of contact with the outer surface of the flange 30. The pattern on the wheel 21 to be embossed on the same side should extend out to the edge of the flange 31 and for a distance away from the edge of the flange at least equal to the width of the portion of the same side to be acted on by this wheel.

10 The peripheral surface of the extension 30 of the wheel 21 over which the flange 31 extends is left plain for a width equal to the overlap of the widest portion of the flange 31, and the pattern on the wheel 20 extends from this plain portion for a distance at least equal to the width of the portion of the same side to be acted on by this wheel.

The purpose of having the pattern wheels of each pattern unit independently rotatable is that they shall rotate at slightly differential peripheral speeds. This result is secured in the machine shown by having each wheel mounted to turn freely on the shaft 22 so that as different more or less raised portions 25 of the peripheries of the wheels engage the side of the came or strip being embossed the wheels will thereby be caused to rotate at relatively slightly varying rates. The result of this is that the patterns on the two wheels 30 of the unit will be constantly shifting relatively to each other, so that the pattern or configuration embossed on the same side will not be repeated on successive revolutions of the pattern wheels but will be constantly 35 varied due to the slight shifting of the pattern wheels relatively to each other. Usually it will be best to depend on the variations in the peripheral surfaces of the wheels to produce the desired differential movement 40 of the two wheels, each being free to turn on the shaft, rather than to provide means for causing a controlled definite slight differential movement of the independently rotatable wheels, or even to resort to a drag 45 on one of the wheels. In either case, the wheels may be considered as independently rotatable.

By forming the two pattern wheels of a unit one with a tapered lateral extension and the other with a thin outwardly tapered flange to overlap such extension, the formation of a longitudinally extending rib on the same side such as would otherwise be formed in the space between the peripheries of the 50 two pattern wheels is avoided, and the line or shoulder between the portions of the pattern formed by the two wheels is greatly minimized. And by forming the overlapping flange with an undulating edge the 55 presence of a straight shoulder or line on the side of the came is avoided and such longitudinally extending shoulder as is formed is rendered less noticeable and less objectionable.

60 While it will usually be desirable to make

the two pattern wheels of each pattern unit of the same diameter and mount them on a common shaft, it is, of course, not necessary that they should be of the same diameter, and if not of the same diameter they would 70 not be mounted on a common shaft. The peripheries of the two wheels must, however, be in the same plane at the point of contact with the came or strip.

It will be understood that the term "embossing" is used herein in a broad and general sense. Obviously, a machine by which a distinct pattern in intaglio is formed on a came or other strip might come within the invention as claimed.

What is claimed is:

1. In an apparatus for embossing strip material, the combination of a pattern unit comprising a plurality of independently rotatable pattern wheels mounted side by side to present to the strip a peripheral embossing surface which is partly on each wheel, and means for supporting the strip pressed against said embossing surface and for causing a relative movement between the pattern unit and the strip, the wheels being caused to roll against the strip, and to rotate at different rates, the axis of each wheel being perpendicular to the direction of such relative movement.

2. In an apparatus for embossing strip material, the combination of a pattern unit comprising a plurality of pattern wheels mounted side by side to present to the strip a peripheral embossing surface which is partly on each wheel, and means for supporting the strip pressed against said embossing surface and for causing a relative movement between the pattern unit and the strip whereby the wheels are caused to roll against the strip and to rotate at slightly different rates, each wheel being free to rotate independently of the other or others, and the axis of each wheel being perpendicular to the direction of such relative movement.

3. In an apparatus for embossing strip material, the combination of a pattern unit comprising two independently rotatable pattern wheels mounted side by side to present to the strip a peripheral embossing surface which is partly on each wheel, and means for supporting the strip pressed against said embossing surface and for causing a relative movement between the pattern unit and the strip whereby the wheels are caused to roll against the strip, one of said wheels having an inwardly tapered lateral extension of its peripheral surface and the other of said wheels having a lateral flange extending over said lateral extension.

4. In an apparatus for embossing strip material, the combination of a pattern unit comprising two independently rotatable pattern wheels mounted side by side to present

to the strip a peripheral embossing surface which is partly on each wheel, and means for supporting the strip pressed against said embossing surface and for causing a relative movement between the pattern unit and the strip whereby the wheels are caused to roll against the strip, one of said wheels having an inwardly tapered lateral extension of its peripheral surface and the other of said wheels having a lateral flange extending over said lateral extension and having an undulating edge.

5. In an apparatus for embossing strip material, the combination of a pattern unit comprising a plurality of pattern wheels mounted side by side to present to the strip a peripheral embossing surface which is partly on each wheel, each wheel being free to rotate independently of the other or others 15 and said wheels being of the same diameter and being mounted on a common shaft, and their embossing surfaces differing in form, and means for supporting the strip pressed against said embossing surface and for causing a relative movement between the pattern unit and the strip in a direction perpendicular to said shaft, whereby the wheels are caused to roll against the strip and because of difference in form of their embossing surfaces are caused to rotate at slightly 25 different rates.

6. Apparatus for embossing strip material, comprising supporting and feeding means for supporting the strip and for moving it 35 longitudinally, and a pattern unit comprising two independently rotatable pattern wheels mounted side by side in position to press against the strip and to present to the strip a peripheral embossing surface which 40 is partly on each wheel, the axis of each wheel being perpendicular to the direction of movement of the strip, said wheels being adapted to roll against the strip as the strip is moved by the supporting and feeding 45 means and being caused to rotate at different rates.

7. Apparatus for embossing strip material, comprising a supporting and feeding wheel, and a pattern unit comprising a plurality of independently rotatable pattern 50 wheels mounted side by side in position to press against the strip and to cooperate with

the supporting and feeding wheel and to present to the strip a peripheral embossing surface partly on each wheel as they roll 55 against the strip, the axes of all said wheels being parallel, and the pattern wheels being caused to rotate at different rates.

8. A came embossing machine, comprising in combination a pair of feeding wheels 60 adapted to engage the web of the came and to support a side thereof, and a pattern unit comprising two independently rotatable pattern wheels mounted to press and roll against the outer face of the supported side of the 65 came as the came is moved by the feeding wheels, each pattern wheel bearing on a part of the came side, the axes of all said wheels being parallel, and the pattern wheels being caused to rotate at different rates. 70

9. A came embossing machine, comprising in combination a pair of feeding wheels adapted to engage the web of the came and to support a side thereof, and a pattern unit comprising two independently rotatable pattern wheels mounted to roll against the outer face of the supported side of the came as the came is moved by the feeding wheels, each wheel bearing on a part of the came side, and one of the wheels having an inwardly tapered lateral extension of its peripheral surface and the other wheel having a lateral flange extending over said lateral extension and having an undulating edge. 75

10. A came embossing machine, comprising in combination a pair of feeding wheels adapted to engage the web of the came and to support the sides thereof, and two pattern units mounted on opposite sides of the path of the came, each pattern unit comprising two independently rotatable pattern wheels mounted to press and roll against the outer face of one of the came sides as the came is moved by the feeding wheels and at the place where the came sides are supported 90 by the feeding wheels, each pattern wheel bearing on a part of the came side, the axes of all said wheels being parallel, and the two wheels of each pattern unit being caused 95 to rotate at different rates. 100

In testimony whereof I have hereunto set my hand.
